UNITED STATES PATENT OFFICE.

DAVID WILSON WOOD, OF BRAZIL, INDIANA.

COIN-CONTROLLED LOCK.

1,041,396.

Specification of Letters Patent. Patented Oct. 15, 1912.

Application filed December 2, 1911. Serial No. 663,509.

To all whom it may concern:

Be it known that I, DAVID W. Wood, a citizen of the United States, and a resident of Brazil, in the county of Clay and State of Indiana, have invented a new and Improved Coin-Controlled Lock, of which the following is a full, clear, and exact description.

My invention relates to a coin-controlled lock, and more particularly relates to locks on doors to rooms, to enter which rooms a charge is made.

An object of my invention is to provide a lock of the above indicated character, in which the coin will remain in view after the door is unlocked and will remain in this position until the door is opened from the inside.

A further object of my invention is to provide a lock of the above-identified character in which it will be possible to open the door from the inside but once after each coin inserted.

A further object of my invention is to provide a mechanical means for registering the number of times the unlocking device is actuated.

A further object of my invention is to provide a lock of the above indicated character in which it is not possible to insert a second coin until the door is in position to admit a second occupant.

A further object of my invention is to provide means whereby the door may be closed by gravity without slamming or without retracting the bolt of the lock.

I attain the above outlined objects by positioning within the lock-casing, a bolt normally in projected position, which is locked in such position by an actuating locking lever, said locking lever actuated by a coin which permits the outer knob to actuate the bolt, which bolt is also actuated by an inner knob, the actuation by said inner knob causing a punch to perforate a roll of paper, and, at the same time, to disengage said lever from its locked engagement with the bolt and to withdraw the bolt, to permit the door to be opened from the inside. I further provide a catch-holding means on the frame of the door, which permits the bolt while in projected position, to engage the means on the frame of the door without actuating the bolt.

With the above and other objects in view as will more fully hereinafter appear, the

present invention consists in certain novel details of construction and arrangement of parts hereinafter fully described, illustrated in the accompanying drawings, and more particularly pointed out in the appended claims.

Reference is to be had to the accompanying drawings, forming a part of this specification, in which similar characters of reference indicate corresponding parts in all the figures, and in which—

Figure 1 is a side elevation of the lock and holding means with the back of the casing removed to show the internal mechanism and with the bolt in locked position; Fig. 2 is a view similar to Fig. 1 but showing the bolt in retracted position; Fig. 3 is a transverse sectional view taken on the line 3—3 of Fig. 1; Fig. 4 is an enlarged perspective view of the locking lever; Fig. 5 is a similar view of the bolt; Fig. 6 is a transverse sectional view showing the punching device, and Fig. 7 is a fragmentary side elevation of the locking lever and bolt, viewed from the side opposite that shown in Figs. 1 and 2.

As shown in the drawings, there is mounted upon a door A, a lock B more particularly forming the subject-matter of this invention, the bolt of which is adapted to engage a ratchet catch C mounted upon the frame of the door. The lock B comprises a casing 7 of any suitable construction extending from opposite sides of which casing is an actuating inside knob 8 passing through the door A, and extending in the opposite direction from the casing is a separate outside knob 9. Within the top of the casing 7 is a coin slot 10 disposed in the path of which coin slot is a substantially L-shaped lever 11 pivoted intermediate its length at 12, to one side of the casing and so disposed relative to the slot 10, that a coin 13 inserted in said slot will fall on the portion 14, of the lever 11, swinging the opposite slot-closing end 15 into position, as shown in dotted lines in Fig. 1, closing the slot 10. The coin in the position shown in dotted lines in Fig. 1, is confined between the inner side of the casing B, and a partition 16 spaced from said wall a distance substantially equal to the thickness of the coin inserted. The coin rests upon the end 17 of a locking lever 18, which is fulcrumed by supporting the same on a pin extending through the aperture 19, and has extending from

lateral sides and on the end adjacent the end receiving the coin, a latch 20, which latch normally rests in a pocket 21 on the top of and to the rear of the locking bolt 22, which locking bolt is disposed to one side of and parallel with the locking lever 18 and extends through a recess 23 on the front edge of the casing 7, to engage with the locking member on the frame hereinafter described.

10 As shown more particularly in Fig. 2, this coin-raising member 18 disengages the latch 20 from the pocket 21, so that by rotating the spindle 24 by turning the knob 9, a stud 25 rigidly mounted on the knob shaft 15 permanently engages a recess 26 in the side of the bolt 22, said bolt being actuated, throws the same into the retracted position shown in Fig. 2, permitting the door to be opened. The movement of the lever 18 is 20 limited by means of a pin 27 mounted on a bracket 28, the head 29 of which pin is disposed beneath the end 17 and is maintained in this position by means of a coil spring 30 having one end bearing under the head 29 and 25 the opposite end resting on the bracket 28.

Mounted in the rear of the casing and in rear of the bolt 22, is the recording device, comprising a pair of drums, the lower drum 31 being mounted on standards 32 projecting 30 from the bottom of the casing 7 and the upper drum 33 having rigidly affixed to one side thereof, a ratchet wheel 34 mounted on a pin 35 projecting from the rear face of the casing. Pivotaly mounted to the rear side 35 of the bolt 22 and positioned below the inner end of the locking lever 18, is a pawl 36 adapted to engage the teeth on the ratchet 34. The under side of the pawl is adapted to be engaged by a transversely-disposed 40 pin 37 projecting from one side of an offset projection 38 mounted on the side of the lever opposite the bolt 22.

With the bolt in the above position, a person may pass into the room closing the door 45 behind him, thus throwing the bolt outwardly and causing the same to engage within laterally disposed recesses in the sides of a cylinder 40 pivotally mounted within a casing 41 on a stud 42, which casing is suitably mounted on the frame of the door. The 50 top of the cylinder 40 has formed thereon radially-disposed one-way ratchet teeth 43 engaged by a pawl 44, which pawl is mounted on a suitable boss 45 within the 55 casing 41.

It will be seen by this construction that the bolt when in its projected position, swings in the direction of free movement of the cylinder 40 and engages the recess 39 in its 60 path, rotating the cylinder 40 until the recess is in line with the bolt. The door, of course, cannot be opened without withdrawing the bolt, as the pawl 44 prevents the cylinder from operating in the direction to open said 65 door. The bolt is maintained in its pro-

tracted position by means of a suitable spring 46, one end of which is fastened to the forward portion of the casing 7 and the opposite end is attached to a pin 47 on the top of the bolt 22.

To open the door from the inside, the knob 8 is rotated, which raises a fan-shaped cam 48, the bearing 49 of which cam bears upon the under side of the locking lever 18, raising said locking lever a distance sufficient to permit the coin to drop into the lower portion of the casing 7, and, at the same time, disengages the latch 20 from the pocket 21 and permits a finger 50 positioned within a recess 51 on the side of the bolt 22 and rigidly maintained on the shaft 52 carrying the knob 8, to bear against the rear wall of said recess to withdraw the bolt.

Mounted in the rear of the shaft 52 and positioned from the rear side of the casing 7, is a bracket 53 mounted within which is a sleeve 54 having a pocket 55 in the rear thereof, the rear open end of which pocket is closed by a screw cap 56 bearing on one end of a spring 57 within said recess, the opposite end of which spring bears upon a punch 58. The point 59 of this punch is adapted to perforate a roll of paper 60 mounted upon the drums 31 and 33. Adapted to bear upon the head 56 is a finger 61 rigidly mounted upon the shaft 52. It will be seen that by this construction, the retraction of the bolt in opening the door, will cause the finger 61 to press the point 59 into the paper, causing the same to be perforated, and thereby registering the number of actuations of the bolt. The pawl 36 moves the ratchet 34, bringing the roll of paper into position, to receive the perforation. Opening the door by means of the inside knob, perforates the paper, and opening the door by means of the outside knob, causes the pawl 36 to move the ratchet wheel 34, bringing the roll of paper into position to be again perforated by the punch 38.

The cam 48 has a quadrant-shaped slot 62 within which is positioned a pin 63 rigidly mounted in the side of the casing, which permits the limited movement of the cam, and a spring 64 having one end attached to the cam and the opposite end attached to the bottom of the casing, positions the cam in its initial position when pressure is withdrawn from the knob 8; a projection 65 extending from the periphery of the cam 48, engages the curved recess 66 within the under side of the locking lever 18, preventing the actuation of the bolt until a coin is inserted to raise the lever 18. When there is no coin on the lever 18, the end of the cam 48 engages in the curved recess 66 and stops the actuation of the bolt 22. When a coin is dropped into the box, it raises the lever 18, so that the end 17 will drop on the head 29, raising the recess to clear the end of the cam 48, and the projection 65 en-

gages the under side of the lever 18, raising it so that the end 17 will drop low enough to permit the escape of the coin, and, at the same time, disengages the pawl 36, permitting the ratchet 34 to remain stationary.

Should it be desired to unlock the door without the necessity of inserting a coin, there is provided a keyhole 67, permitting the insertion of a key to engage a stop 68 on the top of the locking bar 18 and to one side of the keyhole, so that the key will press on this stop to raise the locking bar, as shown in Fig. 2.

Having thus described my invention, I claim as new and desire to secure by Letters Patent:

1. In a lock, a bolt having a pocket upon its upper face, a locking lever extending parallel with and beside said bolt, said locking lever having a latch adapted to engage said pocket, said lever adapted to be actuated by a coin falling on the end opposite the latch, to withdraw said latch from said pocket, a knob shaft, a fan-shaped cam carried by said shaft adapted to engage the under side of said lever, and a finger carried by said shaft, engaging said bolt to withdraw the same after the cam has disengaged the finger on the lever from the pocket in the bolt.

2. In a coin-actuated lock, a casing having a coin slot in the upper edge thereof, a partition disposed below said coin slot, the distance from the wall of said casing being substantially equal to the thickness of the coin, to form a coin compartment, a lever pivoted below said coin compartment, means for viewing the coin in said compartment, a bolt, means locking said bolt in said lever, and means maintaining said coin in sight until said bolt has been twice actuated.

3. In a coin-actuated lock, a bolt, a locking lever adapted to engage said bolt to lock the same in projected position, spring controlled means supporting one end of said

lever, means maintaining a coin on said supported end of said lever, and manually controlled means acting against said support, to precipitate the coin from said lever.

4. In a coin-controlled lock, a casing having a slot therein, a bolt normally projecting from said casing, a knob projecting from the outside of the door, means permitting the actuation of said bolt by said outside knob when a coin is inserted in said slot, means actuated by said coin closing said slot, an inside knob adapted to actuate said bolt, and means actuated by said inside knob uncovering said slot.

5. In a lock, a bolt having a pocket in its upper face, a locking lever extending parallel with and opposite said bolt, said locking lever having a latch adapted to engage said pocket, said lever adapted to be actuated by a coin falling on the end opposite the latch to withdraw said latch from said pocket, a knob shaft, a cam carried by said shaft adapted to engage the under side of said lever, and a finger carried by said shaft engaging said bolt to withdraw the same after the cam has disengaged the finger on the lever from the pocket in the bolt.

6. In a coin-actuated lock, a casing having a coin slot in the upper part thereof, a partition disposed below said coin slot, the distance from the wall of said casing being substantially equal to the thickness of the coin, to form a coin compartment, a lever pivoted below said coin compartment, a bolt, means for locking said bolt in said lever, and means maintaining said coin in position until said lock has been twice actuated.

In testimony whereof I have signed my name to this specification in the presence of two subscribing witnesses.

DAVID WILSON WOOD.
